Attorney

UNITED STATES PATENT OFFICE

HENRY G. KLOPP, OF SPOKANE, WASHINGTON

WINDOW FRAME

Application filed April 17, 1929. Serial No. 355,865.

My present invention relates to improvements in window frames and the improvements are embodied in the construction of the frame, as it is fashioned at the factory, for the purpose of accurate and convenient assembly of the parts of the frame on the job or at the place of the building construction of which the frame is to form a part. My invention involves particularly the construction of the pulley stiles and the blind stops, the former being the side, upright rails of the frame, and the latter being wooden strips that are secured to the stiles and co-operate with parting strips to form the groove in which the upper sash slides.

By the utilization and embodiment of my invention in the window frame, the parts of the frame may be shipped to the job and there assembled with convenience and accuracy; a weather tight joint between the pulley stile and the blind stop is insured; warping of the parts is prevented; and a permanently true groove is provided in which the sash may slide without binding. The parts may also be accurately assembled without the necessity for use of special tools and also without necessity for skilled labor.

The invention consists in certain novel combinations and arrangements of parts as will hereinafter be more fully set forth and claimed. In the accompanying drawings I have illustrated one complete example of the physical embodiment of my invention, and a slight modification thereof, in which the parts are combined and arranged according to one mode I have thus far devised for the practical application of the principles of my invention.

Figure 1 is a horizontal perspective view in section at one side of a window frame, showing the improvements of my invention, it being understood that a similar construction is used at the other side of the frame.

Figures 2 and 3 are sectional views of a portion of a pulley stile with wedge-shaped or dove-tail tongues and of a blind stop or strip having complementary grooves in its face.

Figure 4 is a sectional view partly in per-

spective of a portion of a window frame in which a single tongue and groove are used. Figures 5 and 6 are sectional views showing respectively a portion of the pulley stile and a portion of the blind stop of Figure 4.

In Figure 1 a sash rail 1 and the pane of glass 2 are shown to indicate a portion of the upper sash of a window which slides down and up as usual in the groove provided therefor in the window frame.

The window frame comprises the upright or vertical pulley stile 3, (one used at each side of the frame, although only one stile is herein shown), and the parting strip 4 is secured in usual manner in the groove provided in the inner face of the stile.

The groove for the upper sash is formed by the parting strip 4 and the overlapping edge 5 of the blind stop 6, the latter being partly covered by the outer casing 7. The blind stop 6 is wider than the thickness of the pulley stile to provide the overlapping edge 5 for the sash, and a suitable number of nails 8 are used to secure the blind stop to the edge of the pulley stile.

For use as guides in accurately assembling the parts, to secure a weather tight joint, and to interlock the parts to prevent warping, the edge of the pulley stile adjacent the blind stop is provided with a pair of spaced parallel tongues 9 and 10 that are dovetail-shape or wedge-shaped in cross section, and these tongues are fitted into complementary grooves 11 and 12 in the adjoining face of the blind stop. The depth of the grooves is preferably greater than the depth of the tongues in order that the wedge shaped tongues may be forced into the grooves to insure maximum frictional contact of the sides of the tongues with the side walls of the grooves and to hold the adjoining faces of the pulley stile and the blind stop in close contact. These tapering sides of the tongues and tapering side walls of the grooves also insure a tight joint even though shrinkage should take place in either the stile or the blind stop.

The stile and blind stop are thus capable of being assembled with accuracy, as the tongues and grooves act as guides to insure

convenience and true alinement in assembling the parts.

In Figures 4, 5, and 6 a slight modification is shown, wherein the stile 13 has a single tongue 14 and the blind stop 15 has a single complementary groove 16.

As the grains of the stile and blind stop run in different directions, these parts themselves, together with the tongues and grooves, aid in stiffening the frame against warping, and in maintaining the sash-groove in true alinement, thus avoiding the danger of binding to the sash.

In the construction of window frames shown in the prior art, and in customary practice, the tongues and their complementary grooves have straight parallel sides, and the free, outer edge of the tongue may be flat or rounded.

In the manufacture and shipment of window frames, for various reasons, the frames are shipped in knocked down condition, and in transit the frames and their parts are subjected to varying degrees of temperature. The absorption of moisture by the wood swells or expands the wood, while on the other hand, dry, warm, atmospheric conditions result in a shrinking of the wood parts. Then when the parts of the knocked down frame are assembled, it is frequently found that the tongues are warped, they have expanded, or they have contracted under atmospheric conditions. The walls of the grooves having been subjected to varying atmospheric conditions, also have been changed; and the result is that the tongues will not fit the grooves; nor can a tight, weatherproof joint be made with these defective parts.

By the utilization of a tongue that is wedge shaped or dove-tail in cross section, and with the walls of the grooves of complementary formation, I find that the effects of the varying atmospheric changes are nil, so far as the utility of the parts is concerned. With the dove-tail or wedge shaped tongue and groove the former can be forced into the latter and the parts drawn together by the use of a nail or nails.

As shown in Figure 4 the depth of the groove may be greater than the thickness of the dove-tail or wedge-shaped tongue to compensate for a shrinking of the tongue, and yet permit the tongue to be driven or drawn into the groove to insure a tight and weatherproof joint.

It will thus be apparent that the tighter the tongue is driven into the groove, the tighter and more weatherproof will be the joint, and this tightness, or frictional contact of the joint not only eradicates a warped condition from the tongue, but also insures a maximum rigidity in the assembled frame.

Having thus fully described my invention, what I claim as new and desire to secure by Letters Patent is:—

In a window frame, the combination with a pulley stile having a pair of parallel spaced, longitudinally extending, tongues, each of said tongues having the opposite sides thereof correspondingly tapered, thereby defining spaced wedge-shaped elements and an intermediate recess with outwardly diverging walls, a blind stop having a pair of similarly disposed and complementary grooves therein providing, intermediately of said grooves, a tongue interfittingly engaging said recess, said connection when compressed together affording a weathertight joint with stresses and strains substantially equally distributed over the contacting areas of the joint, and a fastening element extending through the wedge of the blind stop and recess of the pulley stile, respectively, in a perpendicular direction whereby to equalize the compressive forces relative to said tapered contacting surfaces.

In testimony whereof I affix my signature.

HENRY G. KLOPP.
